UNITED STATES PATENT OFFICE.

WILLIAM J. CRUMPTON, OF SUPERIOR, WISCONSIN, ASSIGNOR, BY MESNE ASSIGNMENTS, TO WILLIAM R. HEATH, OF BUFFALO, NEW YORK.

ACCOUNTING DEVICE.

1,084,611.

Specification of Letters Patent.

Patented Jan. 20, 1914.

Application filed June 11, 1908. Serial No. 437,809.

To all whom it may concern:

Be it known that I, WILLIAM J. CRUMPTON, a citizen of the United States, residing at Superior, in the county of Douglas and State of Wisconsin, have invented certain new and useful Improvements in Accounting Devices, (Case 6,) of which the following is a full, clear, concise, and exact description, reference being had to the accompanying drawings, forming a part of this specification.

My present invention relates to accounting devices.

My specific object is to provide means for accounting and indicating in plain figures at all times the amount of time or wages or both for which each of a large number of workmen is to be credited, to indicate at all times the labor cost of each of a large number of jobs and automatically to indicate various totals of wages and job costs as accumulated. While the apparatus herein shown is therefore peculiarly adapted to fulfil this specific object, it may be used for other purposes of like nature.

In a general way, the mechanism of my invention comprises a number of individual wage registers each assigned to a particular workman, also in the preferred embodiment of my invention a number of individual job registers. All of the registers are provided with electromagnetic actuating mechanisms each adapted to cause the one step advancement of the associated register upon the passage of a single current impulse therethrough. Each of the electromagnetic actuating mechanisms associated with a wage register is connected to a source of actuating currents, each actuating current in the present embodiment of my invention comprising a number of electrical impulses. The actuating current is impressed upon the various wage registers in succession, means being provided to impress upon each wage register an actuating current whose effective value, *e.g.*, the number of current impulses, is proportional to the rate of wages of the workman assigned to the individual wage register under actuation. The circuits of the actuating mechanisms for the wage registers are not ordinarily completed and the currents impressed upon the electromagnetic devices are not therefore effective in actuating the associated registers. Any of the electromagnetic

mechanisms for actuating wage registers may, however, be connected in circuit with any of the electromagnetic actuating mechanisms associated with job registers. The circuit of any of the wage registers being thus completed and paths afforded for the actuating current when impressed upon the electromagnetic actuating devices, both wage and job registers are actuated by an amount proportional to the effective value of the actuating current. In order that the actuations of wage or job registers may be totalized, I provide a common wire which forms a part of all of the circuits which are successively closed through electromagnetic actuating mechanisms. In this common wire is connected an electromagnetic actuating device associated with a totalizing register. Since all of the actuating currents pass through this common wire and the electromagnetic actuating mechanism connected therein, the totalizing register will be actuated by an amount proportional to the sum of the effective values of the currents passing therethrough and consequently by an amount proportional to the sum of the actuations of the individual registers. The result of the operation of this apparatus is that each workman's specific or individual register indicates at all times the amount of the wages which have been earned by the workman, the job and totalizing registers indicate the total of the wage cost of each job as earned, another totalizing or generic register indicates at all times the cost to date or for the week or some other period for all of the jobs, etc. The general arrangement for operating this system consists of individual plugs associated with each register assigned to the keeping of a workman's time or wages, and multiple jacks associated with each register assigned to each job account. By such means a number of individual workmen's registers may be connected with any particular job, simply by placing the plugs associated with the workmen's registers in the proper jack associated with the particular job to which the several workmen are assigned.

The boards upon which are mounted the terminal plugs associated with the individual registers assigned to the keeping of the individual workmen's accounts, and multiple jacks which are associated with each individual job account, may be all cen-

tered in one place upon one board, or may be distributed in various places, such as in each department, thereby permitting a workman in his respective department to go directly to his place of work and there make his time registration. With such an arrangement, the multiple jacks are duplicated in each department to an extent sufficient to provide connection with all jobs 10 to which the workmen of that particular department might be assigned, and of sufficient capacity to permit all workmen of that department being assigned to any particular job account. Plugs associated with 15 each individual workman's register are not as a rule, duplicated, and terminate only in the department in which the particular workman is usually employed.

These and other features of my invention 20 will be more clearly understood by reference to the accompanying drawings, in which—

Figure 1 shows in diagrammatic form the general circuit arrangement of the system with a typical arrangement of specific and generic registers; Fig. 2 is a front view 25 of a group of registers, together with electromagnetic actuating mechanisms; Fig. 3 is a side view of the same group, and Fig. 4 is a detailed view of an automatic zero stop 30 device associated with certain of the registers.

Referring to Fig. 1, the registers shown in the upper part of the drawing are generally employed for indicating job accounts 35 the registers shown in the lower part of the drawing are generally employed in keeping workmen's wage accounts. In the center of the drawing are shown the plugs and multiple jacks for controlling the operation of 40 the apparatus of the system. The clock-controlled commutators which control and direct the sending of impulses which constitute the actuating currents are shown at the bottom of the drawing.

45 The lay-out of the job accounting registers is as follows: A, B, C, D, E, and F are specific registers assigned to the keeping of individual job accounts. AB, CD and EF are generic registers into which are summed 50 the specific job accounts of A and B, C and D, and E and F, respectively. ABCDEF is a generic register into which are summed all specific job accounts, thus showing the jobs in process. abcdef is a generic register into which are totalized all 55 specific job accounts, thus showing the total jobs undertaken. Q is a register assigned to the recording of labor expended not chargeable to any particular job. Any workman, 60 on duty, but unassigned to a particular job, is connected to this register, and all men made idle for any cause, such as a factory breakdown, would be during that time connected to this register.

65 The arrangement of the wage register is

in some respects similar to that of the job registers: 1, 2, 3, 4, 5, 6, 7, 8, and 9, are specific registers assigned to the keeping of the individual workman's accounts. TW is a generic register assigned to the recording 70 of total wages. NW is a generic register assigned to the keeping of net wages or wages due. PW is a specific register assigned to the keeping of the total paid wages.

The apparatus for providing the actuating currents, each comprising a suitable number of impulses, is shown at the lower part of Fig. 1. In general, this apparatus comprises a clock-controlled driving shaft which operates suitable commutators. One 75 commutator serves to connect the various wage registers successively with the source of current impulses. Another commutator determines the number of impulses which shall flow at each stage in the progress of 80 the register-selecting commutator. The clock-controlled driving shaft is shown at 10. Upon the hub 11 is mounted the intermittent worm 12, this worm engaging the spur gear 13 and thus serving to drive the 85 shaft 14 upon which the spur gear is mounted. The insulating coupling 15 serves electrically to divide the shaft 14 and upon the insulated section is mounted a brush holder 16 in which is secured the brush 17. This 90 brush co-operates with the commutator 18, which is divided into a number of segments equal to the number of individual workmen's registers. In this figure the segments of the selecting commutator 18 are numbered from 1 to 9, the numbering corresponding with the numbering of the registers to which the several segments are connected. The rotation of the selecting shaft 95 14 serves to establish connection successively 100 with the several registers by virtue of the contacts established between the brush 17 and the various sectors of the selecting commutator.

The impulse-controlling commutator 21 is 110 associated with a brush 20 and holder 19 mounted upon the driving shaft 10 and rotating therewith. This commutator, as shown in the drawings, is composed of seven segments, 0', 1', 2', 3', 4', 5', 6', the insulation between the several segments being wider than the brush 20, so that the connection with one segment will be broken before it is established with the next segment. Current is supplied to these commutators from 115 a battery 22, preferably formed in two sections, as shown. The circuit may be traced from this battery through the impedance coil 101, the conductor 23, the current regulator or ballast 24, the electromagnet windings 25_{NW} and 25_{TW}, the switch 26, conductor 27, and thence to the brush 28, which rides upon the collector ring 29, which is mounted 120 upon the driving shaft 10. It is the function of the impulse-control- 130

ling commutator 21 to determine the number of impulses which shall flow through each of the circuits established by means of the selecting commutator 18. To this end, the segments 1', 2', 3' and 4' of the impulse commutator 21 are connected by means of the conductor 30_{1,2,3,4} with the brush 31_{1,2,3,4}, which is associated with the contact which is associated with the slip ring 32_{1,2,3,4}. The segment 5' of the commutator 21 is connected by means of the conductor 30₅ with the brush 31₅ which rides upon the periphery of the slip ring 32₅. The segment 6' of the impulse commutator 15 is connected by the conductor 30₆ with the brush 31₆, which rides upon the slip ring 32₆. The segment 0' of the commutator 21 is not operatively connected in the main 20 circuits of the system. Parts of the peripheries of the slip rings 32₅ and 32₆ are covered with insulating material 33₅ and 33₆, as shown.

The impulse commutator coöperating with the three slip rings mounted upon the selector shaft 14 impresses four impulses of current upon certain of the selector commutator segments, five impulses upon other segments and six impulses upon others. The 25 slip ring 32_{1,2,3,4} is the only one always in electrical connection with its brush and therefore in constant connection with segments 1', 2', 3', 4' of the commutator 21. The relation of these parts is such as to permit the transmission of four electrical impulses from the brush 31_{1,2,3,4} to the selector brush 17 during each revolution of the driving shaft 10. The worm and worm wheel connection between the driving shaft 40 and the selector shaft serves to cause the step-by-step advancement of the selector shaft. When the selector shaft has been advanced through a sufficient angle, the insulation 33₅ upon the periphery of the slip ring 32₅ passes beyond the brush 31₅, thus causing an electrical connection to be established between the segment 5' of the impulse commutator and the brush 17 of the selector commutator. After this connection 45 has been established, five electrical impulses will be transmitted from the impulse commutator to the selector brush with each revolution of the driving shaft 10. Upon the further advancement of the selector shaft 50 the metallic portion of the periphery of the slip ring 32₆ will be brought into connection with the associated brush 31₆, thus establishing a connection between the segment 6' of the impulse commutator and the selector brush 17. Thereupon each revolution of the impulse brush will cause six electrical impulses to be impressed upon the selector brush 17 and its operation will be continued 55 until the slip rings 32₅ and 32₆ again reach the positions shown in the drawing in which

the insulating sectors 33₅ and 33₆ cut off the connection between the segments 5' and 6' of the impulse commutator and the selector brush 17. The arrangement is such that four impulses are impressed upon each 70 of the segments 1, 2 and 3 of the selector commutator, five impulses are impressed upon each of the segments 4, 5 and 6, and six impulses are impressed upon each of the segments 7, 8 and 9. 75

Leading from each of the selector commutator segments to one of the individual workmen's registers is a conductor. These connecting conductors are respectively designated 34₁, 35₁, 34₂, 35₂ . . . 34₉, 35₉, the subscript corresponding to the number designating the individual register to which the conductor leads and corresponding also with the number of the segment of the selector commutator with which connection is established. These conductors connect in each instance directly with the low resistance winding 25 of the electromagnet for actuating the associated register. The opposite terminal of the low resistance winding 25, 90 is connected with a contact spring 36₁. The contact point 37₁ of this spring normally makes connection with the contact point 38₁ mounted upon a contact spring 39₁. The contact spring 39₁ is connected by means of 95 the conductor 40₁ to a plug 41₁. In like manner the low resistance electromagnet windings associated with the other individual registers are connected through contact springs with connecting plugs 100 41₂, 41₃ . . . 41₈ and 41₉.

Without stopping at this point to describe in detail the manner in which the electromagnet windings serve when energized to actuate the associated registers, I shall trace 105 the paths by which the circuits may be completed back to the other pole of the battery. These circuits ordinarily include in each instance an electromagnet for actuating a job register. The individual job registers are designated A, B, C, D, E and F and their low resistance electromagnet windings 25_A, 25_B . . . 25_F. Each of these electromagnet windings is connected with one or more sets of multiple springjacks, one 110 set being located in one department of a factory and the other set or sets being located in other parts of the establishment. The sets of springjacks located at one point are designated respectively 42_{A1}, 42_{B1} . . . 42_{F1}, and those at the other point 42_{A2}, 42_{B2} . . . 42_{F2}. It will be noted that there are more springjacks to each set in the first mentioned location than in the second. This is due to the probability that there will be more 115 workmen to make connection with the various jobs at the first location than at the second. The nine springjacks connected with each job register, as shown in the drawing, permit nine workmen's plugs and reg- 120 130

isters to be connected simultaneously with any individual job register. A circuit may be traced from any of the springjacks, for example, those in bank 42_{A2}, through conductor 43_{A2}, low resistance winding 25_A, contact springs 36_A and 39_A, and thence through conductors 44 and 45, the low resistance electromagnet winding 25_{AB}, the conductor 46, the low resistance electromagnet winding 25_{ABCDEF}, the electromagnet winding 25_{abcdef}, conductor 48, the impedance coil 102, and thence back to the pole of the other half of the battery 22. The switches 49 and 50 serve normally to connect in series the two halves of the battery 22. It will be seen that with this arrangement of circuits the insertion of any plug into any springjack will cause the closure of a circuit through the low resistance electromagnet winding associated with an individual wage register and through the low resistance electromagnet winding of an individual job register and the electromagnets of one or more totalizing registers. The switches 49 and 50, together with their contacts 51 and 52, are provided for the purpose of throwing the two sections of the battery into parallel relation by moving the switches to their alternate positions. The voltage is thus reduced for a purpose to be more fully described.

Before taking up the operation of the system I shall describe the detail of the electromagnetic mechanisms for actuating the registers.

Referring particularly to Figs. 2, 3 and 4, in which like characters of reference are applied to corresponding parts, I have illustrated at 65 a vertical frame member upon which the registers and the electromagnets 66 for actuating them are mounted, the electromagnets being attached by means of the bolts 67. The plunger armature 68 is adapted to reciprocate within the helical windings of the electromagnet, the collar 69 serving to prevent the rotation of the armature rod. The forward and reverse ratchet pawls 71 and 72 are pivotally attached to the armature at 70. A spring 74 surrounds the armature rod between the collar 69 and a loose washer 73, which is pressed by the spring against the heads of the pawls 71 and 72, this collar and spring mechanism serving to maintain the pawls in engagement with their ratchet wheels. The connection between the register and its ratchet wheels involves a pinion 79 mounted upon the end of the register spindle and meshing with a return driving gear 78. The driving gear is attached to a forward ratchet wheel 75 and a reverse ratchet wheel 76 and to a locking wheel 77, which is fastened to and mounted between the ratchet wheels. This group, comprising ratchet wheels, locking wheel and driving gear, is loosely mounted

upon the shaft 80, the collar 87 serving to maintain the position of the gears and ratchet wheels upon the shaft 80. The pawls 71 and 72 are respectively adapted for engaging the ratchet wheels 75 and 76. The locking wheel 77 cooperates with a wedge-shaped projection 81 upon the end of the plunger-like armature. When the armature is moved into its forward position, as shown in the illustration of the upper register in Fig. 3, the wedge is driven between a pair of teeth on the lock wheel and thus prevents the register or its driving mechanism from being moved too much or too little upon the actuation of the pawl and ratchet mechanism due to the energization of the associated electromagnet. A spring 83, cooperating with a collar 82 upon the end of the armature rod, serves to retract the armature of the electromagnet after its actuation due to a flow of current through the electromagnet winding. The iron pole piece 85 is attached to the plunger rod 68 and the energization of the electromagnet winding causes the attraction of this iron pole toward the pole 86 of the electromagnet; a brass disk at 84 limits the retractive motion of the armature rod. 88 is a lever having on its front end the forward and reverse locking dogs 89 and 90, respectively. These dogs 89 and 90 respectively engage the forward and reverse ratchet wheels 75 and 76. The locking dog lever 88 is pivoted to the frame 65 by means of the pin 91. The front plate of the register mechanism is indicated at 99, openings being provided at 100, through which the figures upon the register indicating wheels may be read. The registers are intended normally for forward actuation and the mechanism is shown in position for such operation. This is due to the fact that the shaft 80 has been moved to the right, as shown in Fig. 2, so that the forward pawl 71 is in alignment with the forward ratchet wheel 75, the reverse pawl 72 being thrown out of alignment with the reverse ratchet wheel 76. The shafts 80 may be moved toward the left, thus bringing the reverse ratchet mechanisms into play. In either position the appropriate member of the lever 88 is brought into engagement with the proper ratchet wheel 75 to cooperate with the pawl mechanism in causing the step-by-step operation of the driving mechanism upon the repeated energization of the associated electromagnet. In either event also the locking wheel is in a position to be engaged by the wedge-like projection upon the armature rod with the flow of each current impulse, thus to prevent the overthrowing of the driving mechanism upon the sudden actuation of the electromagnet armature. It will thus be apparent that by shifting the shafts 80 to the right or to the left a forward or reverse actuation of the registers 130

may be secured by energizing the associated electromagnets. In Figs. 2 and 3 the electromagnetic actuating mechanisms associated with the upper registers are shown in their energized or actuated position, the lower register mechanisms are shown in the position prior to energization.

Each of the individual registers is provided with an arm 60, as best illustrated in Figs. 2 and 4, this arm being associated with a cam 95 on the numeral wheel of highest order. This arm, operating through the insulating member 61, serves to control the contact spring 39. Whenever the numeral wheel 97 of highest order is moved reversely from zero to nine the cam surface 96 engages pin 94 in the side of the switch-actuating arm 60, thus causing an upward motion of this arm mechanically separating the switch springs 36 and 39, their electrical separation being accomplished because of the block 62 of insulating material upon which they are mounted. This reverse actuation of the numeral wheel of highest order to a position below that of zero takes place only when the register mechanism is automatically returned to its zero position. The operation of this mechanism and its utility in the system will be more fully explained.

The operation of the mechanism thus far described is as follows: As shown in the accompanying drawings the ratio of the earning capacities of workmen 1, 2 and 3 to the workmen 4, 5 and 6 and to the workmen 7, 8 and 9 is as 4 to 5 to 6. This ratio corresponds with the rates of wages equal to twenty cents per hour, twenty-five cents per hour and thirty cents per hour, respectively. Assuming that workman No. 1 commences work at seven o'clock in the morning on job A, he will insert the plug 41₁ into one of the multiple jacks 42_{A1}, establishing electrical connections as indicated by the dotted line connecting these two switch members. Assuming the selector shaft 14 to be driven at the rate of fifty revolutions per hour and that each electrical impulse passing an electromagnetic actuating mechanism causes the advancement of the associated register wheels an amount sufficient to indicate one-tenth of one cent, impulses are made to flow over a circuit which may be traced from the positive pole of the battery 22, through the impulse-controlling brush 20, and then successively through the impulse commutator segments 1', 2', 3' and 4' by way of the collector ring 32_{1,2,3,4} and the selector brush 17, to segment No. 1 on the selector commutator. Thence these four current impulses may be traced through the conductors 34₁ and 35₁, the electromagnet winding 25₁ and the switch springs 36₁ and 39₁, to the plug 41₁, thence from the multiple jacks 42_{A1}, through the electromagnet winding

25_A and the associated switch springs and conductors 44, 45 and 46, to the electromagnet windings 25_{ABCDEF} and 25_{abcde}, and thence to the negative pole of the battery 22. Since the impulse-controlling brush 20 makes one complete revolution while the selector brush 17 is retained in each of its successive positions, four impulses will be sent over this circuit each time that the brush 17 makes a revolution and comes into contact with the selector segment No. 1. This means that four times fifty impulses will be sent over this circuit during each hour that the connection of the plug with the springjack is maintained. For each hour that this connection is maintained, therefore, the workman's wage register will be actuated to increase its registration twenty cents; so also the job register A will be advanced twenty cents. If at eight a. m. workman No. 4 also commences work on job A, he will insert his plug 41₄ in another of the springjacks of the set 42_{A1}. When, therefore, the selector brush establishes connection with the segment No. 4 and the impulse commutator causes five impulses to be impressed upon this segment, the impulses will find circuit and flow through the electromagnet winding of the workman's individual wage register No. 4 and thence through the plug 41₄ and jack 42_{A1} connection through the electromagnet winding of the job register A, and thence back to the negative pole of the battery. The circuit of this actuating current will be closed over this circuit fifty times per hour, thus causing the flow of 250 impulses per hour. These impulses will cause the advancement of the wage register assigned to workman No. 4 by an amount represented by twenty-five cents (his hourly wage). So long as plugs 41₁ and 41₄ are connected with the springjacks assigned to job register A four impulses will be caused to flow through the actuating magnet whenever the selector brush makes connection with segment No. 1 and five impulses will be caused to flow each time that the selector brush establishes connection with the segment No. 4. Thus nine times fifty or 450 impulses will be caused each hour to flow through the electromagnet of job register A. This will cause the hourly advancement of this register by an amount corresponding to forty-five cents. This means that job A is charged each hour with the sum of the wages of the workmen who are busy upon that job. No matter how many of the individual workmen may be assigned to this particular job, the job register will be actuated by an amount equal to the sum of the actuations of the individual wage registers. When any of the workmen, as, for example, No. 1, discontinues work upon job A, he withdraws his plug, thus depriving the wage register of a circuit

through which the actuating impulses may flow and depriving also the job register of the impulses which it formerly received through the circuit including the individual wage register No. 1. Assuming that workman No. 7 commenced work in another department on job B, he will insert his plug 41₇ as indicated by dotted line, into a springjack of the bank 42_{B2}. It will readily be understood that with each revolution of the selector brush six current impulses will be caused to flow over a circuit including the energizing electromagnets of the individual wage register 7 and the job register B. Thus a total of 300 impulses per hour will be caused to flow over this circuit, causing the actuation of the workman's wage register to indicate the earnings at the rate of thirty cents per hour and the actuation of the job register to charge job B with a labor cost of thirty cents per hour. So long as circuits are closed through the electromagnets of job registers A and B, all of the current impulses flowing through these two individual job registers will flow through the energizing electromagnet 25_{AB} of the generic job register AB. By this arrangement it is possible to indicate the total labor cost of a job in the register AB and to indicate the labor cost of the various detailed parts of the whole job in the individual job registers A and B. If, for example, workman No. 1 has spent three hours at twenty cents upon the specific job A, his individual register will credit him with sixty cents for accrued wages. Workman 4, having spent two hours upon this same specific job A, will have earned fifty cents at the rate of twenty-five cents per hour. The individual job register A will indicate the total of sixty cents and fifty cents, namely \$1.10. Workman No. 7 having spent one hour upon job B will have caused the actuation of his wage register to indicate thirty cents accrued wages, the job register B will have been actuated by a like amount, indicating that the specific job B is to be charged with a labor cost of thirty cents. The total of the labor cost for the jobs A and B will be indicated in the register AB as \$1.40, the sum of the indications in the specific job registers A and B. In like manner the generic job cost registers ABCDEF and abcdef will be actuated by amounts equal to the total actuations of all the specific job registers.

If the foreman had had no job upon which he could set workman No. 2 at work when he reported in the morning, this workman would have inserted his connecting plug 41₂ in a multiple jack of the set 42_{Q1}. This bank of springjacks leads by way of conductor 43_Q through the actuating electromagnet 25_Q of a waste or lost time register Q. This connection is indicated by a dotted line. Whenever the foreman is able to as-

sign workman No. 2 to one of the jobs A, B, C, D, E, or F, the plug is withdrawn from the bank of jacks marked 42_{Q1} and inserted in the springjack leading to the actuating mechanism of one of the job registers. Register Q takes account, therefore, of all of the wages which must be paid to workmen but which can not be charged directly against a specific job or jobs. It will be understood, of course, in this connection, that while the appropriate number of current impulses is intermittently impressed upon all of the actuating mechanisms assigned to individual wage registers at all times, there will be no actuation of those registers whose energizing circuits are not completed by the insertion of the appropriate plug in some one of the springjacks leading to the negative pole of the battery or other source of current.

The net wage register NW and the total wage register TW are each provided with an energizing electromagnet 25_{NW} and 25_{TW} respectively, these energizing electromagnets being included in the common wire of the circuit in the manner shown in Fig. 1. If, in addition to the wages earned by workmen Nos. 1, 4 and 7, which have been charged against jobs A and B, workman No. 2 has spent two hours of time at twenty cents per hour which can not be charged against any specific job, the lost time register Q will have been actuated by an amount equal to forty cents. While, therefore, the net job register ABCDEF and the total job register abcdef will each indicate \$1.40, the sum of the wages earned by workmen Nos. 1, 4 and 7, or, better, the amounts charged against the individual jobs A and B, the wages equal to forty cents so due workman No. 2 will appear in the lost time register Q and also as a part of the grand total, equal to \$1.80, in the net wage register NW and the total wage register TW.

In the use of this system it is preferable to permit the accumulation of the workmen's wages until the end of some period for which payment is made, commonly at the end of each week. The job registers may be permitted, on the other hand, to continue their operation and accumulation of labor cost until the jobs are completed. The wages due each workman can be read at the end of the week from the individual wage registers and these registers thereupon restored to the zero position to commence the accumulation of the next week's wages. The labor cost of any job or any specific portion of a general job may be read at any time from the job registers. The total labor cost of any job may be read from the appropriate job register when the job has been finished.

We come now to a consideration of the method of restoring the registers to their zero positions and the accounting results

which may be secured in connection with this restoration. The restoration of the registers, if accomplished automatically in the system herein disclosed, had best be done at 5 night time or when none of the workmen is at work upon any job. If, for example, job E has been finished and job register E is to be restored to zero, the cost keeper will first throw the switches 49 and 50 into their alternate positions, thus putting the two sections of the battery in multiple and reducing the voltage impressed upon the circuit. He will then establish a connection between some job restoring plug, as, for example, 59_s, and 10 a springjack of the bank 42_{E1}. The controlling shaft 80 of register E will be pulled out toward the right, as shown in Fig. 2, thus bringing the reverse pawl and ratchet mechanism into play. Current impulses will 15 be caused to flow over this closed circuit, and these impulses will cause the reverse actuation of the job register E, this actuation being continued until the register is brought to the zero position. The next impulse will 20 actuate the register reversely, turning all of the numeral wheels to show a figure 9 and consequently turning the numeral wheel of highest order into the position in which its 25 cam 96 will throw the bar 60 to open the switch contacts 37_E and 38_E, thus opening the circuit of the magnet energizing coil 25_E. The associated energizing winding 63_E is of relatively high resistance and the sections of the battery when connected in multiple are of insufficient voltage to cause the 30 actuation of the register due to the energization effected by this magnet winding. The job register will, therefore, be restored to its zero position and one step beyond, but 35 no further actuation will ensue even though the current impulses continue to flow over this circuit. In thus restoring the individual job register to its zero position, the cost keeper will also thrust the shaft 80 associated with the job register ABCDEF into the reverse position so that this register will 40 be actuated reversely to the same extent as is the individual job register. The job totalizing register abcdef is provided with a 45 short-circuiting switch 47 and conductor 46'. The cost keeper will close this short-circuiting shunt around the totalizing register. In this manner the generic register ABCDEF will be made to indicate the net of the actuations of the specific job registers. The totalizing register abcdef will, on the other hand, be involved only with positive actuations corresponding with positive actuations 50 of the individual job registers and will, therefore, indicate all jobs which have at any time been accounted for in the individual job registers.

The decumulation of the individual job register E involves in the manner previously 55 explained one surplus impulse, this impulse

being required to return the numeral wheel of highest order to the first position below that of zero for the purpose of opening the switch contacts in the circuit of the low resistance actuating electromagnet. This surplus impulse which has been caused to flow in the decumulation of the register E flows also through the generic register ABCDEF. In order to restore the specific job register E to its zero position and to connect the 70 error in the actuation of the generic register it is necessary for the cost keeper after the decumulation has automatically been effected, to throw the switches 49 and 50 in position to connect the two sections of the battery 22 in series and thus to raise the voltage of the battery to its maximum; then to throw the shafts 80 of the registers E and ABCDEF into the position for forward operation and then to cause the flow of a single 75 current impulse through the electromagnet windings of these two registers. This may be done with the plug 59_s in the jack 42_{E1} as above described by moving the switches 47 and 26 into connection with the wires 46' 80 and 23 respectively with the switches 56, 57 and 58 in their closed positions. For this circuit condition the switches 49 and 50 are closed in series with each other until the brush 16 has made contact with the section 85 8 of the commutator 18, at which time the plug 59_s is removed from the jack 42_{E1}, which interrupts the circuit above described. The several switches are then restored to 90 their normal operating condition. The high voltage of the battery is sufficient to cause a flow of current through the electromagnet winding 63_E of a strength sufficient to actuate the ratchet mechanism, thereby causing the numeral wheels to return to their zero 95 position and the switch contacts in the circuit of the low resistance electromagnet winding to be closed. This same current impulse causes also the one step advancement of the electromagnetic actuating mechanism associated with the generic register ABCDEF. The closure of the short-circuiting shunt about the register abcdef is maintained during the flow of this correcting impulse and this totalizing register is not therefore affected in any way by the restoration and resetting of the specific job registers. After the resetting impulses have restored 100 the other job register, the switch 47 is thrown into the alternative position indicated in the drawings, whereupon the electromagnetic actuating mechanism of the register abcdef is effectively connected in circuit.

The decumulation of the workmen's individual wage registers is accomplished in much the same manner as has already been described in connection with the job registers. When any of the workmen's wage register is to be decumulated, the associated 125 130

plug is inserted in the strip of spring jacks 55. Circuit is thus closed from the impulse controlling apparatus through the electromagnetic actuating mechanism of the wage register, thence to the strip of spring jacks 55, then by way of the conductors 54 and 53 to the negative pole of the source of current. When the shaft 80 associated with such a register is thrown into the reverse position, 10 the registers will be decumulated as in the case of the individual job registers as decumulation is automatically continued until the zero position of the register is reached. Thereafter but a single impulse flows, this 15 impulse serving to open the switch contacts in the circuit of the low resistance electromagnet winding, and putting the high resistance winding alone in circuit. If this decumulating operation has been effected as 20 it should be with the two sections of the battery in multiple, the high resistance winding will prevent the flow of sufficient current to continue the actuation of the register beyond the first position below zero. Any number 25 of wage registers may, of course, be decumulated at the same time in the manner which will be understood from the previous descriptions of this system.

It will be noted that the pay-roll register 30 PW is included in circuit between the conductors 54 and 53. This register is equipped with ratchet mechanism for operation in both directions and with the shaft 80 as in the case of the individual registers. When 35 the position of the shaft 80 of any of the individual registers is thrown into the reverse position for the purpose of decumulation, the shaft 80 associated with the pay-roll register will also be thrown into the reverse position. The pay-roll register wheels are, however, numbered in the reverse direction so that while the wage-register is being decumulated, the pay-roll register will be correspondingly operated in the forward direction. After the decumulation of any 45 wage registers, it is necessary for the attendant to cause the flow of a single current impulse from the batteries connected in series in order to restore the decumulated wage 50 registers to zero. These restored impulses serve also to correct the errors in the operation of the pay-roll register, there being, of course, one surplus impulse through each of the wage registers. The pay-roll register 55 serves to totalize the wages as they are decumulated from the individual wage registers. The pay-roll register indicates, therefore, the total of the wages which are to be paid to the various individual workmen.

The net wage register NW and the total wage register TW operate in a manner quite similar to that described in connection with the net job and total job registers. The electromagnetic actuating mechanisms of the

registers NW and TW are ordinarily included in circuit in the manner shown in the drawing. During the forward actuation of the individual wage registers, therefore, both the net and the totalizing wage registers are forwardly operated. When the wage registers are decumulated, usually at a time when the workmen are paid off, the switch 26 will be thrown into position to connect with the short-circuiting wire 23. The totalizing wage register is therefore prevented from operating while the decumulation is being effected. The electromagnetic actuating mechanism of the net wage register is, however, retained in circuit and its controlling shaft 80 being adjusted in the manner already described, the net wage register serves to indicate at all times the total of the readings of all of the individual wage registers. When all of the wage registers are decumulated and stand at their zero positions the reading of the net wage register will also be zero. The totalizing register TW serves at all times to indicate the total of all of the wages which have been earned. If the decumulation of the registers is carried on at night or when it is unnecessary to drive any of the registers in the routine manner, the impulse controlling apparatus may be speeded up so as to send the impulses at a very rapid rate, thereby causing decumulation much more rapidly than would otherwise be the case. In order that the net wage register NW and the total wage register TW may not be affected by the clearance of the job registers a short-circuiting wire 23 is provided. When the switch arm 26 is thrown into connection with the terminal of this wire 23, neither of the registers NW nor TW will be actuated. These registers are made, therefore, to take account solely of the operation of the wage registers as a whole.

The various registers could, of course, be turned back to zero manually and quite conveniently in a small system, especially if it were not desired to transfer the indications of some registers into other registers, such as the generic registers herein described.

In case of overtime, where the men are paid at a different rate than for regular time, the shaft 10 is driven at the proper speed to make the records in accordance with the rate of pay. During the noon hour and all other nonworking hours, the impulse sending mechanism may be brought to rest or the course of current disconnected, either automatically or manually, thus preventing any registration even though certain workmen were unduly early in registering in or unduly late in registering out. If the impulses are sent only during working hours, a workman can receive no credit for any other time spent upon the premises.

The switch 56 shunts the contact wheel 32₅

and the switch 57 shunts the contact wheel 32₆. Thus upon closing both of these switches the same number of electric impulses is impressed upon each workman's individual wage register. These switches 5 may be thrown in clearing the registers in order that the largest possible number of impulses may be impressed upon the registers with each revolution of the controlling shaft 14. If the switch 58 is closed, together with the switches 56 and 57, the commutator 21 is shunted as are also the contact wheels 32₁, 32₂, 32₃, 32₄, 32₅ and 32₆. With the switches in this position one electrical impulse is impressed upon each individual register during each revolution of the controlling shaft 14, the making and break of the circuit being controlled entirely at the commutator 18. When the switches are thus thrown the system is put in proper condition for recording the workmen's time in hours and the keeping of the time expended upon each job in hours irrespective of the various rates of wages which may perhaps be earned by the various workmen. If the effect of the commutator 21 and the contact wheels is eliminated by closing the switches 56, 57 and 58, the device is reduced to a time-accounting system. If, however, the switches and various other devices are in the position shown in the drawing, and operating as previously described, the system becomes more than a time-accounting mechanism, namely, a wage-accounting system taking account of the varied rates of pay of the different workmen.

It will thus be seen that in the operation of my system the individual workmen may be assigned to any jobs and changed about at any time and as frequently as may be desired without in any way interfering with the proper operation of the system. So also any workmen's wages may be properly accounted for even though it be impossible to assign him to any particular job and to charge the job with the wages as earned. The various generic registers may be arranged to indicate such totals and net results as may be desirable from an accounting standpoint.

A change of rate for any workman may be secured by simply changing the connection of his registers and establishing different relations with the impulse and selector 55 commutators.

Although the battery and ballast are arranged to operate as a source of constant current in order to take care of any variations in the resistances of the various operative 60 circuits which are successively closed and also to enable the actuation of any and all of the registers which may be connected in at any one time, I have provided still further means for checking in the operation of the 65 system. This in a general way comprises a

source of alternating current which is superimposed upon the operative circuits and the strength of this alternating current is depended upon to control the operation of the impulse sending mechanism, the strength of the alternating currents being determined 70 in turn by the operation or failure to operate of the electromagnetic actuating mechanisms. An escapement wheel 126 is mounted upon the end of the driving shaft 10. This escapement wheel co-operates with a locking armature 127 controlled by the electromagnet 124. The retraction of the armature being effected by the spring 128. When the magnet 124 is energized with a current 75 of sufficient strength, the locking armature 127 will engage a tooth of the escapement wheel 126 and prevent the rotation of the driving shaft and the mechanism controlled thereby. The source of alternating current 80 which is superimposed upon the circuits is indicated in these drawings by the windings 103 and 105 of a transformer, an alternating current of high frequency being supplied to the primary winding 103. Winding 112 of the relay magnet 113 is connected in circuit with the secondary winding 105. The winding 107 of the other relay magnet 108 is included in the circuit which leads through the circuits of the accounting system. This circuit may be traced from the wire 104, through the secondary winding 105 of the transformer, thence through the wire 106 and the electromagnet 108 by way 90 of the wire 109, the condenser 110 and the wire 111 to the wire which leads to the impulse controlling mechanism. The impedances 101 and 102 which are included in circuit at either side of the battery sections prevent the battery from short-circuiting 95 the alternating current apparatus. The operation of this mechanism is as follows: When the impulse controlling mechanism and the selector brush close a circuit for direct current through one or more register 110 actuating mechanisms, the superimposed alternating current will begin to flow also over the same circuit, this alternating current flowing through the electromagnet winding 107. When this circuit is first 115 closed, the armatures of the electromagnetic actuating mechanisms will be in their retracted positions. The electrical impedance of the actuating electromagnets will not, therefore, be so high as when the armatures 120 have been attracted. Before the armatures have been attracted the impedance of the energizing circuits is so low that a very considerable alternating current is caused to flow through the electromagnet winding 107. The adjustment of the alternating current 125 governing relay is so made that this strong energization of the magnet winding 107 will overpower the effect of the magnet 112 upon the vibrating armature 113, thereby 130

- causing upward movement of the left hand end of its armature to close the circuit between the contacts 119 and 120. The closure of this circuit causes current to flow from the positive pole of the battery 22, through the conductor 125 to the electromagnet 124, and thence by way of the conductor 123, the armature 115, the contacts 119 and 120 back to the negative pole of the source of direct current. The consequent energization of the electromagnet 124 will cause the associated armature 127 to be thrust forward against the tension of the spring 128, thus interposing the lock 127 in the escapement wheel 126. The driving mechanism will thus be locked against operation and this condition will continue until all of the armatures in the circuit over which the energizing current flows have been attracted.
- 20 When the armatures of the electromagnetic actuating mechanisms have been attracted the impedance of the circuit will be increased. This will cut down the flow of alternating current, thereby weakening the magnet 108 of the alternating current relay. The magnet 113 of this differential relay will, therefore, overpower the magnet 108 and cause the retraction of the armature 115 into the position shown in the drawings, 25 opening the circuit between contacts 119 and 120. The opening of the energizing circuit of the magnet 124, of course, causes the deenergization of this magnet and the consequent retraction of the armature 127.
- 30 Under ordinary conditions this deenergization of the electromagnet 124 will take place very promptly after the energizing circuit has been closed through the electromagnet actuating mechanisms of the system. The 35 operation of this detent device will be very rapid, therefore, and will not serve to interfere with the driving of the impulse controlling mechanisms. If, however, any one of the armatures of the electromagnetic actuating mechanisms is sluggish in its operation, the locking mechanism will detain the driving mechanism until the sluggish armature has been attracted, thereby causing the 40 proper actuation of the associated register.
- If, for any reason, the electromagnetic actuating mechanism becomes so far deranged that its armature cannot be attracted to cause the operation of the associated register, 45 the automatic locking mechanism will stop the operation of the impulse controlling devices and maintain them in fixed position until the attendant, noting the interruption, has had time to seek out the difficulty and to 50 correct it. In order that the attendant may be notified of any such stoppage of the operation of the system, I provide a signal in the form of a sluggish relay 129 included in a parallel circuit with the electromagnet 124.
- 55 When, under ordinary circumstances, this electromagnet is energized for but an instant, the sluggish relay will not be actuated to close the circuit controlled thereby. When, however, the electromagnet 124 is energized for a longer interval, as upon the failure of some electromagnet mechanism to operate its armature, the sluggish relay will close circuit through the local circuit of the signal bell 129, the actuation of this bell serving to notify the attendant of the 60 arrangement. Thus my invention provides means for the normal operation of the system in the manner previously described and for providing a prompt and effective signal in case of any failure.
- 65 While I have herein shown and described a preferred embodiment of my invention, it will be apparent to those skilled in the art that many changes may be made without departing from the spirit thereof, and I do not 70 wish, therefore, to be limited to the specific details herein described, but
- 75 What I claim as new and desire to secure by Letters Patent is:
1. In combination, a source of electric current impulses, a plurality of individual registers each having its separate electromagnetic actuating mechanism and adapted to be actuated by said current impulses, means for connecting any of said registers with said source of current impulses, and means for totalizing the actuations of all of the individual registers. 80
2. In combination, a source of electric current impulses, a plurality of individual registers each having its separate electromagnetic actuating mechanism and adapted to be actuated by said current impulses, means for connecting any of said registers with said source of current impulses, and means for totalizing the actuations of all of the individual registers. 85
3. In combination, a source of electric current impulses, a plurality of individual registers each having its separate electromagnetic actuating mechanism and adapted to make a one step advancement upon the passage of a single current impulse there-through, means for connecting any of said registers in circuit with said source of current impulses, a totalizing register, and means for actuating the totalizing register by an amount proportional to the sum of the actuations of the individual registers. 90
4. In combination, a plurality of individual registers, means for supplying actuating currents of different effective characteristics to such registers, an electromagnetic actuating mechanism associated with each of the individual registers, the degree of actuation of each register being dependent upon the effective characteristics of the actuating current which traverses the associated electromagnetic actuating mechanism, means for connecting any of the individual registers with the means for supplying said actuating currents, and means for automatically indicating the total of the actuations of all of the individual registers. 95
5. In combination, a plurality of devices for causing the flow of actuating currents, each of which actuating currents comprises a different number of impulses, a plurality of individual registers each adapted to make 100
- 105
- 110
- 115
- 120
- 125
- 130

a one step advancement upon the passage of a single current impulse therethrough, and means for connecting any of the individual registers with any of said devices.

5. In combination, a plurality of devices for causing the flow of actuating currents, each of which actuating currents comprises a different number of impulses, a plurality of individual registers each adapted to make 10 a one step advancement upon the passage of a single current impulse therethrough, means for connecting any of the individual registers with any of said devices, and means for automatically indicating the total of the 15 actuations of all of the individual registers.

6. In combination, means for supplying in succession actuating currents of different effective characteristics, a plurality of individual registers, an electromagnetic actuating 20 mechanism associated with each individual register, the degree of actuation of any register being dependent upon the effective characteristics of the current which traverses the electromagnetic actuating 25 mechanism associated therewith, and means for connecting the electromagnetic actuating mechanisms in succession with said current supplying means.

7. In combination, means for supplying in 30 succession actuating currents of different effective characteristics, a plurality of individual registers, an electromagnetic actuating mechanism associated with each individual register, the degree of actuation of 35 any register being dependent upon the effective characteristics of the current which traverses the electromagnetic actuating mechanism associated therewith, means for connecting the electromagnetic actuating 40 mechanisms in succession with said current supplying means, and means for automatically totalizing the actuations of the individual registers.

8. In combination, a plurality of devices 45 for causing current impulses of different rates, a plurality of individual registers each adapted to make a one step advancement upon the passage of a single current impulse therethrough, and means for connecting any individual register with any of 50 said devices.

9. In combination, a source of electric current impulses, a plurality of individual wage registers, a plurality of individual job 55 registers, an electromagnetic actuating mechanism associated with each of said wage and job registers each adapted to cause the one step advancement of the associated register upon the passage of a current impulse therethrough, means for connecting any of the electromagnetic actuating mechanisms associated with the wage registers in circuit with any of the electromagnetic actuating mechanisms associated with any of the individual job registers, means for 60 connecting any such pair of interconnected electromagnetic actuating mechanisms with said source of current impulses, means for automatically totalizing the actuations of the individual wage registers, and means for automatically totalizing the actuations of 125 the individual job registers.

individual job registers, and means for connecting any such pair of interconnected electromagnetic actuating mechanisms with said source of current impulses. 65

10. In combination, a source of electric current impulses, a plurality of individual wage registers, a plurality of individual job registers, an electromagnetic actuating mechanism associated with each of said wage and job registers each adapted to cause the one step advancement of the associated register upon the passage of a current impulse therethrough, means for connecting any of the electromagnetic actuating mechanisms associated with the wage registers in circuit with any of the electromagnetic actuating mechanisms associated with any of the individual job registers, means for connecting any such pair of interconnected electromagnetic actuating mechanisms with said source of current impulses, and means for automatically totalizing the actuations of the individual wage registers. 80

11. In combination, a source of electric current impulses, a plurality of individual wage registers, a plurality of individual job registers, an electromagnetic actuating mechanism associated with each of said wage and job registers each adapted to cause the one step advancement of the associated register upon the passage of a current impulse therethrough, means for connecting any of the electromagnetic actuating mechanisms associated with the wage registers in circuit with any of the electromagnetic actuating mechanisms associated with any of the individual job registers, means for connecting any such pair of interconnected electromagnetic actuating mechanisms with said source of current impulses, and means for automatically totalizing the actuations of the individual job registers. 95

12. In combination, a source of electric current impulses, a plurality of individual wage registers, a plurality of individual job registers, an electromagnetic actuating mechanism associated with each of said wage and job registers each adapted to cause the one step advancement of the associated register upon the passage of a current impulse therethrough, means for connecting any of the electromagnetic actuating mechanisms associated with the wage registers in circuit with any of the electromagnetic actuating mechanisms associated with any of the individual job registers, means for 110 connecting any such pair of interconnected electromagnetic actuating mechanisms with said source of current impulses, and means for automatically totalizing the actuations of the individual job registers. 115

13. In combination, a source of electric current impulses, a plurality of individual wage registers, a plurality of individual job registers, an electromagnetic actuating mechanism associated with each of said wage and job registers each adapted to cause the one step advancement of the associated register upon the passage of a current impulse therethrough, means for connecting any of the electromagnetic actuating mechanisms associated with the wage registers in circuit with any of the electromagnetic actuating mechanisms associated with any of the individual job registers, means for connecting any such pair of interconnected electromagnetic actuating mechanisms with said source of current impulses, means for automatically totalizing the actuations of the individual wage registers, and means for automatically totalizing the actuations of the individual job registers. 120

14. In combination, a plurality of devices

for causing electric current impulses of different frequencies, a plurality of individual wage registers, a plurality of individual job registers, an electromagnetic actuating mechanism associated with each wage register and with each job register, the said electromagnetic actuating mechanisms each being adapted to cause the one step advancement of the associated register upon the passage of a current impulse therethrough; and means for connecting the electromagnetic actuating mechanism associated with any wage register in circuit with the electromagnetic actuating mechanism associated with any job register, each pair of interconnected actuating mechanisms being connected with one of said devices.

14. In combination, a plurality of devices for causing electric current impulses of different frequencies, a plurality of individual wage registers, a plurality of individual job registers, an electromagnetic actuating mechanism associated with each wage register and with each job register, the said electromagnetic actuating mechanisms each being adapted to cause the one step advancement of the associated register upon the passage of a current impulse therethrough, means for connecting the electromagnetic actuating mechanism associated with any wage register in circuit with the electromagnetic actuating mechanism associated with any job register, each pair of interconnected electromagnetic actuating mechanisms being connected with one of said devices, a wage totalizing register, and means for actuating the wage totalizing register by an amount proportional to the sum of the actuations of the individual wage registers.

40 15. In combination, a plurality of devices for causing electric current impulses of different frequencies, a plurality of individual wage registers, a plurality of individual job registers, an electromagnetic actuating mechanism associated with each wage register and with each job register, the said electromagnetic actuating mechanisms each being adapted to cause the one step advancement of the associated register upon the passage of a current impulse therethrough, means for connecting the electromagnetic actuating mechanism associated with any wage register in circuit with the electromagnetic actuating mechanism associated with any job register, each pair of interconnected electromagnetic actuating mechanisms being connected with one of said devices, a job totalizing register, and means for automatically actuating the job totalizing register by an amount proportional to the sum of the actuations of the individual job registers.

60 16. In combination, a plurality of devices for causing electric current impulses of different frequencies, a plurality of individual

wage registers, a plurality of individual job registers, an electromagnetic actuating mechanism associated with each wage register and with each job register, the said electromagnetic actuating mechanisms each being adapted to cause the one step advancement of the associated register upon the passage of a current impulse therethrough, means for connecting the electromagnetic actuating mechanism associated with any wage register in circuit with the electromagnetic actuating mechanism associated with any job register, each pair of interconnected electromagnetic actuating mechanisms being connected with one of said devices, a wage totalizing register, means for actuating the wage totalizing register by an amount proportional to the sum of the actuations of the individual wage registers, a job totalizing register, and means for automatically actuating the job totalizing register by an amount proportional to the sum of the actuations of the individual job registers.

17. In combination, a source of electric current, a plurality of individual wage registers, a plurality of individual job registers, an electromagnetic actuating mechanism associated with each of said wage and job registers, means for connecting the electromagnetic actuating mechanism associated with any wage register in circuit with the electromagnetic actuating mechanism associated with any job register, and means for connecting any such pairs of interconnected electromagnetic actuating mechanisms in circuit with said source of current.

18. In combination, a source of electric current, a plurality of individual wage registers, a plurality of individual job registers, an electromagnetic actuating mechanism associated with each wage and job register, means for connecting the electromagnetic actuating mechanism associated with any wage register in circuit with the electromagnetic actuating mechanism associated with any job register, means for connecting any such pairs of interconnected electromagnetic actuating mechanisms in circuit with said source of current, and means for automatically totalizing the actuations of the individual registers of one of said classes.

19. In combination, a source of electrical current impulses, a plurality of individual electromagnetic registering devices, each having its separate electromagnetic actuating mechanism, the degree of actuation of each of which is determined solely by the number of impulses passing therethrough, a totalizing register, and means for automatically actuating the totalizing register by an amount proportional to the sum of the actuations of the individual registering devices.

20. In combination, a plurality of individual

vidual electromagnetic registering devices, means for connecting said individual electromagnetic registering devices successively with a source of current, and a totalizing 5 electromagnetic registering device in a circuit common to said individual electromagnetic registering devices.

21. In combination, a common wire, a plurality of branch circuits connected therewith, a source of current, uniformly actuated means for periodically closing circuit from said source through said common wire and successively through the branch circuits, an electromagnetic registering device included in the common wire, and an electromagnetic registering device included in each of the branch circuits.

22. In combination, a common wire, a plurality of branch circuits connected therewith, a source of current, uniformly actuated means for closing the circuit from said source through the several branch circuits and said common wire in succession, a step-by-step electromagnetic registering device included in the common wire, and a step-by-step electromagnetic registering device included in each of said branch wires.

23. In combination, a common wire, a plurality of branch circuits connected therewith, a source of current, means for periodically closing circuit from said source through said common wire and successively through the branch circuits, an electromagnetic registering device included in the common wire, and an electromagnetic registering device included in each of the branch circuits.

24. In combination, a common wire, a plurality of branch circuits connected therewith, a source of current, means for closing the circuit from said source through the several branch circuits and said common wire in succession, a step-by-step electromagnetic registering device included in the common wire, and a step-by-step electromagnetic registering device included in each of said branch wires.

25. In combination, a plurality of individual registers each assigned to a particular workman's account, means for actuating the said registers at rates proportional to the rates of wages of the workmen, said registers being geared and calibrated to read directly in monetary units of value, means for indicating the total of the actuations of the individual registers, and electrical switching mechanism for connecting the individual registers for operation.

26. In combination, a plurality of individual registers each assigned to a particular workman's account, means for actuating said registers at rates proportional to the rates of wages of the workmen, said registers being geared and calibrated to read directly in monetary units of value, and electrical

switching mechanism for connecting the individual registers for operation.

27. In combination, a register, electromagnetic ratchet mechanism for actuating the register, means for reversing the direction of motion imparted by the electromagnet to the register, a switch in the circuit of the electromagnet, and means associated with the numeral wheel of highest order in said register for controlling said switch. 70

28. In combination, a register, electromagnetic ratchet mechanism for actuating the register, means for reversing the direction of motion imparted by the electromagnet to the register, a normally closed switch in the circuit of the electromagnet, and means controlled by the numeral wheel of highest order in said register to open said switch when the register reaches a predetermined position. 80

29. In combination, a register, electromagnetic ratchet mechanism for actuating the register, means for reversing the direction of motion imparted by the electromagnet to the register, a normally closed switch in the circuit of the electromagnet, and means controlled by the numeral wheel of highest order in said register to open said switch when the register reaches a predetermined position. 85

30. In combination, a plurality of registers provided with electric means for actuating the same, sources of electric impulses of different frequency, and means for establishing circuit connections between any source and any register or registers. 90

31. In combination, a plurality of registers provided each with electromagnetic means for actuating the same, sources of electric impulses of different frequency; a series of switch-terminals connected with said sources, and a coöperating contact-terminal connected with each register for establishing readily separable circuit-connections between any source and any register or registers to operate the same at a rate dependent upon said frequency. 100

32. In combination, a plurality of registers provided each with electromagnetic means for actuating the same, means for generating electric impulses of different frequencies, and readily controlled circuit-connections between said generating means and said registers for selectively determining the rate of actuation of any register. 115

33. In combination, a plurality of registers provided each with electromagnetic means for actuating the same, means for generating electric impulses of different predetermined frequencies, sets of switch-terminals having connections with said generating means such that each set of terminals controls the impulses of a certain frequency independently of any other set, and a contact-terminal connected with each register 120

125

130

adapted to coöperate with any switch-terminal for selectively establishing circuit-connections between said generating means and any one or more registers to actuate the same at a rate dependent upon the particular switch-terminal with which any one register has connection.

34. In combination, a source of electric current, a plurality of time-controlled interrupting devices in circuit therewith, for sending current-impulses through the circuits at different predetermined frequencies, a set of switch-terminals connected with each interrupting device whereby each set of terminals controls the impulses of a certain frequency, a plurality of registers having each electromagnetic actuating means adapted to be energized by said current-impulses, and a contact-terminal connected with each register adapted to coöperate with any switch-terminal for selectively establishing circuit-connections between said source and any one or more registers to actuate the same at a rate dependent upon the particular switch-terminal with which any one register has connection.

35. In combination, a source of electric impulses of predetermined frequency, a plurality of wage-registers, a plurality of corresponding job-registers, electromagnetic means associated with each register to actuate the same at a rate dependent upon the said frequency, and circuit-connections between said source of impulses and said registers for connecting any one or more of the wage-registers each in series with its corresponding job-register to compel simultaneous actuation of any wage-register and its corresponding job-register.

36. In combination, a means for generating electric impulses of different predetermined frequencies, a plurality of wage-registers, a plurality of job-registers, electromagnetic actuating means associated with each register, sets of switch-terminals having connections with said generating means such that each set of terminals controls the impulses of a certain frequency independently of any other set, a contact-terminal connected with each register adapted to coöperate with any switch-terminal to selectively establish circuit-connections between said generating means and any one or more registers to actuate the same at a rate dependent upon the particular switch-terminal with which the register has connection, said circuit-connections compelling simultaneous actuation of any wage-register and its corresponding job-register.

37. In combination, a plurality of registers provided each with electromagnetic means for actuating the same in either direction, devices for causing electric impulses of different frequency, a series of switch-terminals connected with said devices, and a co-

operating contact-terminal connected with each register for establishing readily separable circuit-connections between any of said device and any register or registers to operate the same at a rate dependent upon said frequency. 70

38. In combination, a plurality of registers provided each with electromagnetic means for actuating the same in either direction, means for generating electric impulses of different frequencies, and readily controlled circuit-connections between said generating means and said registers for selectively determining the rate of actuation of any register. 75

39. In combination, a plurality of registers provided each with electromagnetic means for actuating same in either direction, means for generating electric impulses of different predetermined frequencies, sets of switch-terminals having connections with said generating means such that each set of terminals controls the impulses of a certain frequency independently of any other set, and a contact-terminal connected with each register adapted to coöperate with any switch-terminal for selectively establishing circuit-connections between said generating means and any one or more registers to actuate the same at a rate dependent upon the particular switch-terminal with which any one register has connection. 80

40. In combination, a source of electric current, a plurality of time-controlled interrupting devices in circuit therewith for sending current-impulses through the circuits at different predetermined frequencies, a set of switch-terminals connected with each interrupting device whereby each set of terminals controls the impulses of a certain frequency, a plurality of registers having each electromagnetic means adapted to be energized by said current-impulses for actuating the register in either direction, and a contact-terminal connected with each register adapted to coöperate with any switch-terminal for selectively establishing circuit-connections between said source and any one or more registers to actuate the same at a rate dependent upon the particular switch-terminal with which any one register has connection. 100

41. In combination, a source of electric impulses of predetermined frequency, a plurality of wage-registers, a plurality of corresponding job-registers, electromagnetic means associated with each register for actuating the same in either direction at a rate dependent upon the said frequency, and circuit-connections between said source of impulses and said registers for connecting any one or more of the wage-registers each in series with its corresponding job-register to compel simultaneous actuation of any wage-register and its corresponding job-register. 120

42. In combination, a means for generating 130

- electric impulses of different predetermined frequencies, a plurality of wage-registers, a plurality of job-registers, electromagnetic means associated with each register for actuating the same in either direction, sets of switch - terminals having connections with said generating means such that each set of terminals controls the impulses of a certain frequency independently of any other set, a contact-terminal connected with each register adapted to coöperate with any switch-terminal to selectively establish circuit-connections between said generating means and any one or more registers to actuate the same at a rate dependent upon the particular switch-terminal with which the register has connection, said circuit-connections compelling simultaneous actuation of any wage-register and its corresponding job-register.
43. In combination, a source of electric current impulses, a plurality of individual registers each adapted to be actuated by said current impulses, switching means for said registers any of which may be concurrently closed to send current impulses through the corresponding register actuating mechanism, and means for totalizing the actuations of all of the individual registers.
44. In combination, a source of electric current impulses, a plurality of individual registers each adapted to make a one step advancement upon the passage of a single current impulse therethrough, switching means for said registers any of which may be concurrently closed to send electric current impulses through the corresponding register actuating mechanism, a totalizing register, and means for actuating the totalizing register by an amount proportional to the sum of the actuations of the individual registers.
45. In combination, a plurality of devices for causing current impulses of different rates, a plurality of individual registers each adapted to make a one step advancement upon the passage of a single current impulse therethrough, switching means for the individual registers any of which may be concurrently closed with any of said devices, and means for automatically indicating the total of the actuations of all of the individual registers.
46. In combination, a source of electric current impulses, a plurality of individual wage registers, a plurality of individual job registers, an electromagnetic actuating mechanism associated with each of said wage and job registers and each adapted to cause the one step advancement of the associated register upon the passage of a current impulse therethrough, means for connecting any of the electromagnetic actuating mechanisms associated with the wage registers in circuit with any of the electromagnetic actuating mechanisms associated with
- any of the individual job registers, and means for causing current impulses to flow from said source simultaneously through any desired pair of interconnected electromagnetic actuating mechanisms.
47. In combination, a source of electric current impulses, a plurality of individual wage registers, a plurality of individual job registers, an electromagnetic actuating mechanism associated with each of said wage and job registers and each adapted to cause the one step advancement of the associated register upon the passage of a current impulse therethrough, means for connecting any of the electromagnetic actuating mechanisms associated with the wage registers in circuit with any of the electromagnetic actuating mechanisms associated with any of the individual job registers, means for connecting any such pair of interconnected electromagnetic actuating mechanisms concurrently with said source of current impulses, thereby causing the simultaneous advancement of all of the registers associated with the connected electromagnetic actuating mechanisms, means for automatically totalizing the actuations of the individual wage registers, and means for automatically totalizing the actuations of the individual job registers.
48. In combination, a plurality of devices for causing electric current impulses of different frequencies, a plurality of individual wage registers, a plurality of individual job registers, an electromagnetic actuating mechanism associated with each wage register and with each job register, the said electromagnetic actuating mechanisms each being adapted to cause the one step advancement of the associated register upon the passage of a current impulse therethrough, means for connecting the electromagnetic actuating mechanism associated with any wage register in circuit with the electromagnetic actuating mechanism associated with any job register, and means for connecting any such pair of interconnected electromagnetic actuating mechanisms with any of said devices.
49. In a wage-registering system, the combination of a wage-register, a job-register, time-controlled mechanism, and means for connecting such time-controlled mechanism with the wage-register and the job-register by a single operation and thereby effecting the operation of such registers.
50. In a wage-registering system, the combination of a wage-register, a job-register, time-controlled mechanism, and a connecting device for driving both of such registers when such device is connected to the time-controlled mechanism.
51. In a wage-registering system, the combination of a wage-register, a job-register, time - controlled mechanism, and driving

- means for each of such registers, such driving means adapted to be connected to the time-controlled mechanism by a single operation to operate such registers.
52. The combination of a plurality of wage registers, an electromagnetic actuating mechanism for each of said registers, and a job register for establishing operative connection between a desired one of said wage registers and said mechanism, said job register being actuated concurrently with said wage register. 70
53. In combination, a plurality of electromagnetically actuated registers, a source of electric impulses, and means for connecting two or more of such registers with such source to concurrently indicate a transaction in different units. 75
54. In a device of the class described, a wage register, a waste-wage register, a job register, an electromagnetic actuating mechanism associated with each of said registers, a source of current for delivering electric impulses of a predetermined rate, means for connecting the actuating mechanism of each register to said source of impulses, and means for selectively breaking the connection of either the actuating mechanism for said waste-wage register or the actuating mechanism for said job register with said source of impulses. 80
55. The combination of a wage register, an actuating mechanism therefor, and a job register for establishing operative connection between said wage register and said mechanism, said job register being actuated concurrently with said wage register. 85
56. In an accounting system, the combination of an individual wage register, a waste-wage register, a job register, an electromagnetic actuating mechanism associated with each register, a source of electric impulses, connections between said source and said mechanism for actuating said individual wage register concurrently with either one of the other registers, and means for preventing concurrent actuation of the waste-wage register and the job register. 90
57. In an accounting system, a source of electric impulses of a predetermined rate, a waste-wage register, a job register, an electromagnetic actuating mechanism associated with each of said registers, means for connecting the actuating mechanism of said waste-wage register with said source of impulses, means for connecting the actuating mechanism of said job register with said source of impulses, and means whereby the actuating mechanism of said waste-wage register remains disconnected from said source during the connection of the actuating mechanism of said job register with said source. 95
58. In an accounting system, a source of electric impulses of a predetermined rate, a wage register, a waste-wage register, a job register, an electromagnetic actuating mechanism for each of said registers, means for connecting the actuating mechanism of said wage register with said source of impulses, means for connecting the actuating mechanism of said job register with said source of impulses, and means whereby the actuating mechanism of said waste-wage register remains disconnected from said source during the connection of the actuating mechanism of said job register with said source. 100
59. In a device of the class described, the combination of a source of electric impulses, a wage register, a waste-wage register, a job register, actuating mechanism for each of said registers, means for connecting each of said actuating mechanisms with said source of impulses, and means whereby the actuating mechanism of said waste-wage register remains disconnected from said source during the connection of the actuating mechanism of said job register with said source. 105
60. In an actuating system, the combination of a register, electromagnetic mechanism for actuating said register, a source of electric impulses for operating said electromagnetic mechanism, and devices coöperating with said electromagnetic mechanism to clear the register. 110
61. In an accounting system, the combination of a register, electromagnet mechanism for actuating said register, a source of electric impulses for operating said electromagnetic mechanism, devices coöperating with said electromagnetic mechanism to clear the register, and switching mechanism controlled by the register to interrupt the clearing operation. 115
62. In an accounting system, the combination of a wage register, a job register, a waste-wage register, a source of electric impulses, circuit connections extending from said source to said registers, and switching mechanism requiring the inclusion in circuit with said wage register of either the job register or the waste-wage register during an operative interval of the wage register. 120
63. In an accounting system, the combination of a first register, electromagnetic mechanism for actuating said register, a second register, electromagnetic mechanism for actuating said second register, devices for advancing said first register by means of current impulses to a desired reading, and circuit connections for including both of said actuating mechanisms to clear the reading from said first register into said second register by the backward motion of said first register. 125
64. In an accounting system, the combination of a first register, electromagnetic mechanism for actuating said register, a second register, electromagnetic mechanism for 130

actuating said second register, devices for advancing said first register by means of current impulses to a desired reading, circuit connections for including both of said actuating mechanisms to clear the reading from said first register into said second register by the backward motion of said first register, and switching mechanism controlled by said first register for interrupting the clearing operation when said first register is moved to its cleared position.

65. In an accounting system, the combination of a first register, electromagnetic mechanism for actuating said register, a second register, electromagnetic mechanism for actuating said second register, devices for advancing said first register by means of current impulses to a desired reading, circuit connections for including both of said actuating mechanisms to clear the reading from said first register into said second register, and switching mechanism controlled by said first register for interrupting the clearing

operation when said first register is moved to its cleared position.

66. In an accounting system, the combination of a plurality of registers, a source of electric impulses, and distributing mechanism for successively sending said impulses through the actuating mechanisms of said registers.

67. In an accounting system, the combination of a plurality of registers, a source of electric impulses, distributing mechanism for successively sending said impulses through the actuating mechanisms of said registers, and mechanism for sending different numbers of impulses per unit of time through the different register-actuating mechanisms.

In witness whereof, I hereunto subscribe my name this 3rd day of June, 1908.

WILLIAM J. CRUMPTON.
